PURIFICATION OF ALKYL PHENOLS

Samuel Benson Thomas and William C. Smith,
Berkeley, Calif., assignors to Shell Development
Company, San Francisco, Calif., a corporation
of Delaware

No Drawing. Application July 13, 1940,
Serial No. 345,376

11 Claims. (Cl. 260—627)

This invention relates to the desulfurization of alkyl phenols by treating them in the form of vapor with hydrogen at elevated temperatures and at substantially atmospheric pressures in the presence of sulfur-immune hydrogenation catalysts.

The term, alkyl phenols, as used herein refers to acid-reacting hydroxy aromatic compounds consisting essentially of alkyl phenols and containing varying amounts of phenols and impurities such as organic sulfur. Alkyl phenols, sometimes known as "acid oils," are obtained by extracting cracked mineral oil or coal-tar distillates with aqueous solutions of alkali metal hydroxide, and acidifying the alkaline extracts so obtained

Alkyl phenols have a number of important applications. For instance, they are used in the flotation of ores, or in the manufacture of resins, cyclic alcohols, ketones, etc., or as anti-oxidants, disinfectants, selective solvents, etc. The presence of impurities such as organic sulfur compounds frequently impairs the usefulness of the alkyl phenols for these purposes.

It has been known to remove organic sulfur compounds from alkyl phenols by hydrogenation at elevated temperatures and pressures. However, this process results in the reduction of a considerable portion of the phenols as well as of the sulfur compounds. Thus, when employing pressures of the order of 20 or more atmospheres at effective desulfurization temperatures, as heretofore considered necessary, as much as 20% of the alkyl phenols are destroyed.

Now, in accordance with our invention, we have found that alkyl phenols containing sulfurous impurities can effectively be desulfurized without substantial loss of alkyl phenols by treating them in the vapor phase with hydrogen at elevated temperatures and at substantially atmospheric pressure in the presence of sulfur-immune hydrogenation catalysts.

In order that this desulfurization under our conditions shall result in low sulfur content, it is necessary that the major portion of the sulfur compounds, and preferably the entire amount, consist of thiophenols. We have discovered that under our mild hydrogenation conditions, thiophenols can be converted substantially quantitatively to neutral hydrocarbons and readily separable sulfur compounds, such as H_2S , in contrast to certain other sulfur compounds which frequently contaminate alkyl phenol mixtures, particularly thiophenes and related compounds. Therefore, to draw the most benefit from our process, i. e., producing low sulfur content alkyl

phenols without substantial loss in alkyl phenols themselves, it is very desirable to start out with an alkyl phenol mixture which contains as small an amount as possible of the sulfur compounds which are not reducible under our conditions.

Fortunately, most of the hydrogenation-resistant sulfur compounds are neutral, which compounds can be removed from alkyl phenol mixtures at least in part by steaming or washing intensely the alkyl phenol mixtures while in solution of an aqueous alkali, almost any substantially water-insoluble good solvent for the sulfur compounds (which solvent is free from objectionable elements) being suitable for the washing.

As is known, alkyl phenols are normally recovered from cracked petroleum oil or coal-tar distillates by extraction with aqueous solutions of caustic alkali. Together with the acidic components contained in the distillate, a considerable quantity of neutral oils are also dissolved in the aqueous solution, a large portion of which are sulfur compounds of the type difficult to hydrogenate destructively. However, since these compounds are neutral and are merely held in the aqueous solution by virtue of their solubility in the alkyl phenolates, it is possible to remove them, or at least a substantial portion thereof, by the methods indicated above, i. e., by intense steaming or washing with a suitable solvent for sulfur compounds.

In order to recover from hydrocarbon distillates the largest portion of the alkyl phenols contained therein, very strong solutions of aqueous alkali metal hydroxides are usually employed in the extraction, i. e., aqueous solutions containing, for example, 30% to 50% NaOH. The resulting phenolate solutions are excellent solvents for many of the stable neutral sulfur compounds, and in order to expel the latter more readily, it is often advantageous to dilute the phenolate solutions with water prior to washing or steaming them to reduce their solvent powers for the neutral sulfur compounds.

The catalysts that may be employed in accordance with our invention are those hydrogenation catalysts which are substantially immune to sulfur poisoning. For example, it is known that such catalysts comprise metal oxygen compounds not reducible to metals under the reaction conditions or sulfidic compounds, said metal oxygen compounds or sulfidic compounds being derived from the heavy metals of the groups 1, 2, 4, 5, 6 or 8 of the periodic system, or mixtures of these metal oxygen compounds and sulfidic compounds. Of particular advantage are the metal oxygen com-

pounds and the sulfidic compounds of metals from group 6 of the periodic system. The term "metal oxygen compounds not reducible to metal" is intended to comprise metal oxides and hydroxides; furthermore, salts of acids, from which the acid may be driven out by heat, such as carbonates, and also metal oxides or hydroxides which are combined with acids in a complex form such as complex compounds of phosphoric acid or silicic acid with molybdcic acid or tungstic acid, as for example ammonium phosphomolybdate. Oxides of metals, when combined with acid in a non-complex form to form salts from which the acid cannot be volatilized such as sulfates or silicates or phosphates, however, are not comprised within the said term. As examples of metals, from which the oxidic or sulfidic compounds may be derived in the present case, may be mentioned copper, silver (the latter preferably in combination with molybdcic acid, tungstic acid or vanadic acid), zinc, cadmium, tin, lead, vanadium, bismuth, chromium, molybdenum, tungsten, uranium, nickel and cobalt. But, also, the other heavy metals of the aforementioned groups of the periodic system are useful. The compounds obtainable from salts of metal acids of the 5th or 6th group of the periodic system by complete or partial reduction with hydrogen sulfide have a specially advantageous catalytic action.

These catalysts may contain activators such as alkaline earth metals, cesium oxide, thorium oxide, etc. The catalytic substances may be used in pill or pellet form or be deposited on a carrier such as activated alumina, pumice, carbon, silica gel, fuller's earth and the like.

The mol ratio of hydrogen employed to the phenolic feed may be between about 1:9 and 9:1 and preferably in a ratio between about 1:2 and 2:1.

Depending on the catalyst used, the thiophenol content of the alkyl phenols and the alkyl phenol fraction employed, temperatures of treatment may vary from about 200° C. to 420° C. but in some cases higher or lower temperatures may be employed. For most fractions of alkyl phenols, however, a temperature in the range of about 250° C. to 375° C. is sufficient.

To insure selective reduction of the thiophenols without substantial loss of the alkyl phenols, the total pressure on the reactor should in no case exceed 50 lbs. Since pressures but little above atmospheric may cause substantial loss of the alkyl phenols, it is well to maintain in the reactor a pressure not to exceed 20 to 30 lbs., and preferably at about atmospheric pressure.

To enable substantial desulfurization at low pressures, the treatment of the alkyl phenols with hydrogen must be carried out in the vapor phase, for treatment in the liquid phase requires higher pressures of the order of 300 lbs. or higher, and results in loss of a portion of the alkyl phenols.

The following examples further illustrate our invention:

Example I

The vapors of an alkyl phenol fraction boiling in the range of 220° C. to 240° C. and containing about .6% sulfur were passed, together with hydrogen, the mol ratio of hydrogen to the phenols being 1.6:1, over a molybdenum sulfide catalyst deposited on grade-A activated alumina at a temperature of about 350° C. and a total

5 pressure of 16 lbs. The volume of total feed per volume of catalyst per hour was maintained at about .43. Better than 98% of the alkyl phenols containing .057% sulfur were recovered.

Example II

10 The vapors of an alkyl phenol fraction boiling in the range of 220° C. to 240° C. and containing about .6% sulfur were passed, together with hydrogen at a mol ratio of 1.6 hydrogen to 1 mol of the alkyl phenols, over an ammonium phosphomolybdate catalyst deposited on a grade-B activated alumina at a temperature of about 352° C. and a total pressure of about 16 lbs. The volume of feed per volume of catalyst per hour was maintained at about .46. Better than 98% of the alkyl phenols containing .045% sulfur were recovered.

Example III

15 The vapors of an alkyl phenol fraction boiling in the range of 220° C. to 240° C. were passed, together with hydrogen at a mol ratio of 1.6 hydrogen to 1 mol of the alkyl phenols, over a nickel sulfide catalyst deposited on a majolica clay at a temperature of about 332° C. and a total pressure of 16 lbs. The volume of feed per volume of catalyst per hour was maintained at about .46. Better than 98% of the alkyl phenols containing .040% sulfur were recovered.

20 30 We claim as our invention:

1. A process for desulfurizing alkyl phenols containing sulfur-bearing impurities in the form of thiophenols which comprises treating said phenols in the vapor phase with hydrogen at a temperature between about 200° C. and about 420° C. and at a total pressure not to exceed 50 lbs. in the presence of a sulfur-immune hydrogenation catalyst.

2. The process of claim 1 in which the total pressure is substantially atmospheric.

3. The process of claim 1 in which a mol ratio of hydrogen to the phenolic feed is maintained between the limits of 1:9 and 9:1.

4. The process of claim 1 in which the temperature of treatment is about 275° C. to about 375° C.

5. The process of claim 1 in which the mol ratio of hydrogen to the phenolic feed is between the limits of 1:2 and 2:1.

6. A process for the desulfurization of alkyl phenols containing sulfur-bearing impurities in the form of thiophenols comprising treating said alkyl phenols in the vapor phase with hydrogen at a temperature between 200° C. and 420° C. under a total pressure of not more than 50 lbs. and in the presence of a catalyst comprising essentially ammonium phosphomolybdate.

7. A process for the desulfurization of alkyl phenols containing sulfur-bearing impurities in the form of thiophenols comprising treating said alkyl phenols in the vapor phase with hydrogen at a temperature between 200° C. and 420° C. under a total pressure of not more than 50 lbs. and in the presence of a catalyst comprising essentially molybdenum sulfide.

8. A process for the desulfurization of alkyl phenols containing sulfur-bearing impurities in the form of thiophenols comprising treating said alkyl phenols in the vapor phase with hydrogen at a temperature between 200° C. and 420° C. under a total pressure of not more than 50 lbs. and in the presence of a catalyst comprising essentially nickel sulfide.

9. A process for desulfurizing alkyl phenols

containing sulfur in the form of neutral oils and thiophenols comprising the steps of removing said neutral oils from the mixture and contacting the resulting alkyl phenol fraction containing thiophenols in the vapor phase with hydrogen at a temperature between about 200° C. and 420° C. and a total pressure not to exceed 50 lbs. in the presence of a sulfur-immune hydrogenation catalyst.

10. A process for producing alkyl phenols of reduced sulfur content from hydrocarbon oils containing alkyl phenols and sulfur impurities in the form of thiophenols, comprising the steps of extracting said alkyl phenols from said hydrocarbon oils with aqueous alkali metal hydroxide, removing neutral oils from the resulting extract, liberating the alkyl phenols from the

5 extract so purified, and contacting said alkyl phenols in the vapor phase with hydrogen at a temperature between about 200° C. and 420° C. and at a total pressure not to exceed 50 lbs. in the presence of a sulfur-immune hydrogenation catalyst.

11. A process for reducing the sulfur content of alkyl phenols containing thiophenols which comprises treating said phenols in the vapor phase with hydrogen at a temperature between about 200° C. and about 420° C. and at a total pressure not substantially in excess of atmospheric in the presence of a sulfur-immune hydrogenation catalyst.
